UNITED STATES PATENT OFFICE

CHARLES E. WAREAM AND GEORGE W. JOHNSON, OF NORWOOD, OHIO, ASSIGNEES TO THE AMERICAN LAUNDRY MACHINERY COMPANY, OF NORWOOD, OHIO, A CORPORATION OF OHIO

PRESSING MACHINE

Application filed October 9, 1925. Serial No. 61,466.

This invention relates to power operated pressing machines, such as are used for pressing garments and in laundries for ironing wearing apparel.

One object of the invention is to provide an improved power pressing machine embodying a special form of epicyclic gearing in the mechanism between the power motor and pressing head to secure a material and quiet reduction of speed and enable the operating mechanism to be readily reversed for moving the head to and fro.

Another object of the invention is to provide an improved power pressing machine of the type described in which the closing operation is terminated by means sensitive to or governed by or in accordance with the amount of pressure exerted upon the work, such means being adjustable, if desired, to vary the predetermined pressure so produced and being so arranged that under all circumstances and regardless of the thickness of work a uniform and any desired predetermined pressure may be produced.

A further object of the invention is to provide an improved power pressing machine in which the press opening movement is terminated by means actuated by and therefore governed in accordance with the movable pressing member or members, to insure full opening of the press after each pressing operation.

A further object of the invention is to provide an improved power pressing machine of the type before described equipped with safety guard means constructed and arranged not only to stop the motor means in case of impending injury to the operator or obstruction of the guard, but to also initiate and cause the completion of a complete press opening movement or, in other words, to restore the press to initial full open position, thereby releasing from pressure whatever may have caused the obstruction, such as the work or a part of the operator's person.

A further object of the invention is to provide safety mechanism for a press of this kind, including a guard adapted to engage any obstruction to normal movement of the pressing members in closing, said guard be-

ing of special form and sensitive to movement at any point and adapted when its movement is obstructed to not only promptly bring the pressing members to rest, but to reverse the movement of the operating mechanism and restore the head to its full open position.

A further object of the invention is to provide a guard for a press of this kind, which in open press position occupies a position not obstructing full entrance to the pressing space and which guard advances ahead of the head as the latter moves downwardly so as to be engaged by any abnormal obstruction but nevertheless does not proceed beyond the pressing space when the press is fully closed and does not interfere with the lay or set of a garment or other work on the pressing bed.

Further objects of the invention are in part obvious and in part will appear more in detail hereinafter.

In the drawings, which represent one suitable embodiment of the invention, Fig. 1 is a side elevation, the cover of the switch casting being omitted to expose interior parts; Fig. 2 is a rear elevation; Fig. 3 is a detail sectional elevation through the lower portion of the machine on the line 3-3, Fig. 2; Fig. 4 is a detail section of the gearing on the line 4-4, Fig. 5; Fig. 5 is a detail sectional elevation on the line 5-5, Fig. 1; Fig. 6 is a detail elevation of the control switch operating and movement limiting mechanism at the rear of the machine; Fig. 7 is a detail elevation partly in section, through the safety reversing mechanism, the section being taken on the line 7-7, Fig. 2; Fig. 8 is a detail sectional view on the line 8-8, Fig. 7; Fig. 9 is a detail section through the latch rod on the line 9-9, Fig. 7; Fig. 10 is a detail section on approximately the line 10-10, Fig. 2, and illustrating the finger guard and its operating mechanism; Fig. 11 is a detail section illustrating a part of the mechanism actuated by the finger guard, the section being taken on the line 11-11, Fig. 2; Fig. 12 is a detail section of the controlling switch mechanism on the line 12-12, Fig. 6, parts being in elevation; and Fig. 13 is an electric diagram.

The press shown in the drawings comprises a suitable frame 1 on the pedestal of which is mounted the usual heated pressing bed or garment support 2 cooperating with the pressing head 3 supported by the head lever 4 pivoted at 5 in an upward extension of the frame. The rear arm of said lever supports a swivel block 6 in which slides a rod 7 jointed or pivoted at the knuckle pin 8 to a link 9, 10 which in turn is pivoted at 10 to a short link 11 pivoted in the stationary frame at 12. Rod 7 at its upper end above the head lever carries a head 13 and below said lever an adjustable collar or abutment 14 serving as 15 a seat for adjusting the pressure of a compression spring 15, which at its upper end abuts the swivel block 6 before referred to. The rod 7 and link 8 cooperate as toggle members with the knuckle 8, by straightening and breaking of which toggle members the press is closed or opened. The short link 11 is for emergency purposes, the pivot 10 being connected by a link 16 to a pin movable in the slot 17 of one arm of an emergency 20 treadle 18 pivoted at 19 in the frame. This emergency mechanism is of known form adapted for use when the press is closed and if its operating mechanism fails for any reason, under which circumstances the emergency treadle 18 may be depressed to move the link 11 counter-clockwise in Fig. 1 and open the toggle formed by members 11 and 9 and thereby permit the head to rise a short distance sufficient to free an obstruction or 25 prevent burning the padding of the bed. This emergency mechanism forms no part of the present invention and may be omitted, if desired.

The press is operated by any suitable prime mover, such as the electric motor 19, the shaft of which is connected by a universal coupling 20 to a shaft 21 rotatable in suitable bearings in the frame and extending through a hollow casing 22. In said casing are located 25 a fixed gear 23 on the rub of which a sleeve 22^a of the casing rotates and a rotatable gear 24 to which the casing is keyed at 22^b, both of said gears surrounding shaft 21 and of which gears the gear 23 has a slightly smaller pitch diameter than gear 24. Between said two gears, shaft 21 has keyed thereto a spider 25 shown as having three arms, each of which carries a stub shaft 26 supporting two pinions 27, 28 respectively meshing with the stationary gear 23 and the rotatable gear 24 and having pitch diameters corresponding with their mating gears. In other words, the pitch diameter of pinion 27 is slightly greater than that of pinion 28. Gear 24, while rotatable 50 on the shaft 21 is fixed to turn with the casing 22, which at its opposite end is sleeved upon the hub of the stationary gear 23, as stated. The effect of this epicyclic gearing is such that when shaft 21 is driven by the 55 motor it carries the spider 25 and with it the

sets of epicyclic pinions 27, 28 around the shaft axis and thereby produces rotation of the gear 24 and casing 22 in the same direction as the rotation of shaft 21, but at a largely reduced speed proportional to the differential between the pitch diameters of gears 23, 24. Casing 22 is connected by a link 29 to the knuckle 8 between the upper and lower toggle members. Consequently rotation of the casing 22, produced in the manner described, produces crank motion of the connecting pin 30, causing the link 29 to serve as a connecting rod for straightening or breaking the toggle members for closing or opening the press. As will later appear, 70 shaft 21 is driven in opposite directions by the motor 19, with consequent oscillatory movement of the casing 22 and the gearing enclosed therein.

The gear casing 22 is preferably provided 80 with plugged openings 31 through which it may be filled with grease or other lubricant in which the gears run.

The system for controlling operative movement of the pressing members includes certain electric switches for the motor circuit as well as mechanism permitting certain phases of manual control of said system by the operator, other phases of its automatic operation by the machine, and still other 90 phases of its automatic operation in case of unusual or emergency conditions.

Referring first to Figs. 6, 12 and 13, the electric system includes a reversing switch which is indicated generally at 32, Fig. 6. 100 This switch comprises four stationary contacts 37, 38 and two sets of movable contacts, to wit, upper contacts 33 and lower contacts 35. The four stationary contacts 37, 38 are all at the same level. Looking at the switch 105 from the front, as in Fig. 6, two of them, marked 37, are at the left and two of them, marked 38, are at the right. Fig. 12, which is a sectional view taken at right angles to Fig. 6, shows the two stationary contacts 37, 110 which extend vertically and lie parallel to each other.

The four movable contacts 33 are also all at the same level, being presented two to the left and two to the right in Fig. 6, so that they will properly register with and lie opposite to the stationary contacts 37, 38. The four lower contacts 35 are arranged in like manner to the upper contacts, two at the left and two at the right, so as to register properly with the stationary contacts 37, 38.

These two sets of movable contacts, four upper and four lower, are cross connected in pairs by jumpers, one jumper being shown at 34, Fig. 12. These jumpers are wires or bonds of the usual form used in connecting the contacts of electrical switches and the like. The jumpers for the upper set of contacts, however, are arranged differently from those for the lower set of contacts, and spe- 125 130

cifically, the difference is that in the upper set of contacts, as viewed in Fig. 6, one jumper connects the front left contact 33 to the rear left contact 33, this jumper being 5 actually illustrated in Fig. 12, and another jumper connects the front right contact 33 to the rear right contact 33; while in the four lower contacts, one jumper connects the front left contact 35 to the front right contact 35 10 and another jumper connects the rear left contact 35 to the rear right contact 35.

With this arrangement, when the movable contacts of the switch are moved to their upper position, so that the lower contacts 35 15 are effective or function to complete the circuits, each contact 37 is connected by a pair of contacts 35 and jumper to one of the contacts 38, whereas, when the switch is in its lowest position, with the upper contacts 33 20 functioning to complete the circuits, the two contacts 37 are conductively connected and the two contacts 38 are conductively connected, all as indicated in the diagram, Fig. 13. The upper of contacts 33 and their jumpers 25 are mounted on an insulating block 39 with a non-circular, such as a square, opening, so that said block slides vertically but without rotation upon a rod 40. The lower contacts 35 are likewise mounted on a like insulating block 41 also slidable on said rod. The two blocks with their sets of contacts are normally separated by a compression spring 42, which forces the upper block against a collar 43 and the lower block against a collar 44, said collars being secured to the rod 40. Upward motion of the rod in the switch casing is limited by a collar 45 on its lower end adapted to abut the casing. At its upper end said rod is jointed by a link 46 to one arm of 40 a bell crank lever 47, the other arm of which carries a swivel block 48 through which slides a rod 49 jointed at 50 to one arm of the T or three armed lever 51. Between the swivel block 48 and a pin on the rod 49 is a compression spring 52. A second arm of the T lever 51 is pivoted to a rod 53 extending through an opening in a bracket 54 on the machine table 55, said rod being provided with a collar 55^a to limit its forward motion and on its outer end with a button or knob 56 by which it may be manipulated and which limits its rearward motion. The third arm of the T lever 51 has its end formed as a yoke 57 through the opening of which passes the lower end of a rod 58 having rollers 59 beneath said yoke to engage the side members thereof, and which rod extends upwardly and slides through a bearing 60 on a stationary part of the frame, above which it is surrounded by a compression spring 61 abutting a collar 62. Said rod is squared where it passes through the bearing 60, as shown in Fig. 9, to prevent its rotation therein. Its upper end is round and slides in a bearing 55 55 in a stationary bracket 63 clamped on the

pivot shaft 5 for the head lever, as shown in Fig. 10, said rod 58 where it slides through the bracket being provided with a recess 64 to receive a latch 65 on the end of a rod 66 threaded for adjustment endwise in an ear 67 surrounding the head trunnion 5, where it is provided with a slot 67^a slightly elongated in the direction of the length of rod 66, as shown in Fig. 7. Surrounding the ear 67 is a block 68 adapted to turn about the ear as a bearing with swinging movement of the head and to which block is attached a rod 69 connected at its other end (see Fig. 10) to an arm 70 on a shaft 71 extending across the top of the head and journaled in upward extensions from two arms 72 pivoted on the head and lying along side of the side arms of the head lever. At opposite ends of the machine, the shaft 71 is provided with short arms 73 connected to links 74, 35 which on their lower ends are provided with balls 75 lying in sockets in the frame 76 of a guard for the pressing members, said guard having a skirt portion 77 depending along the entire periphery of the head and of open form as shown in Fig. 2. Where the frame members lie along side of the arms 72 they are provided with vertically extending slots 78 to receive pins 79, the arrangement being such that the left hand pin 79 (Fig. 10) serves as a pivot about which the guard turns when its front portion is raised, while the right hand pin 79 serves as a pivot when the rear of the guard is elevated, while both slots permit the front and rear portions of the guard to rise simultaneously on other occasions. When any such motions of the guard occur—and they may occur at either or both ends of the press—either or both of the ball portions 75 are raised, turning one or both of the two arms 73 in the counter-clockwise direction. Each arm 73 has a collar 73^a surrounding the shaft 71 and provided with a shoulder or abutment 73^b adapted to engage a like shoulder or abutment 71^a on a collar 71^b pinned to the shaft 71, the arrangement being such that either arm 73 may alone turn the shaft 71, the shoulder 71^a at the other end of the shaft thereupon moving away from its operating shoulder 73^a. When shaft 71 is so turned it pulls over to the right the rod 69 and (referring to Fig. 7) moves the slotted ear 67 to the right to take up the lost motion in its elongated slot and thereby withdraw the latch 65 from the recess 64, all for emergency control operation, as will later appear.

Referring back, now, to the bell crank lever 47, that arm thereof to which the link 46 is connected is also connected by a link 80 to a yoke like arm 81 pivoted on the machine frame, the pin 82 to which said link 80 is connected carrying a roller 83 adapted for engagement by a shoulder or ledge 84 (see Fig. 1) of the head lever. Said pin also 13^a

supports a swivel block 82^a through which slides a rod 85 having a collar 85^a at its lower end and connected at its upper end to the outer end of a lever 86 pivoted at 87 to the 5 head lever and connected by a link 88 to a lateral extension 89 from the head 13 at the upper end of the upper toggle rod 7.

Referring now to Fig. 10, the side portions of the front head lever arm are provided 10 with downward extensions having bearings for a shaft 90, fastened on each end of which is a bell crank lever 91 having in the free arms thereof rollers 92 adapted to engage plates 94 fast on arms 72 supporting the 15 guard. The other arms of said levers are connected by links 95 to pivots in clevises 96 rigidly secured to the stationary brackets 63^a. Arms 72 are provided at their rear ends with ears 98 supporting adjustable stop 20 screws 99 adapted to engage upward extensions 97 of the brackets 63^a to limit downward swinging motion of the arms 72 and the guard carried thereby.

The operation is as follows:

25 Let us assume that the press is fully closed under pressure with the parts in the position shown in Fig. 1. At any time when the press operating mechanism fails or if, for example, the main current supply should be suddenly 30 cut off or if for any reason it is impossible to open the press, the emergency treadle 18 may be depressed to tilt the pivot forward and break or open the toggles 9, 11. Under ordinary conditions, this emergency opening 35 mechanism is not resorted to, and its parts shown in Fig. 1, remain in the positions there shown.

To open the press, the operator pushes in the knob 56 until it engages the frame bracket 40 54, thereby turning lever 51 in the counter-clockwise direction, Fig. 6. In the closed position of the press shown in Figs. 1, 6 and 13, the switch parts are in neutral position. When the pivot 50 on lever 51 passes beyond 45 a straight line running from the pivot of lever 51 to the swivel block 48 the compression of spring 52 overbalances the parts and completes the final movement of the controlling rod 53 and holds the same in its new position. 50 Likewise the compression effect of spring 52 is exerted upon the swivel block 48 and snaps the depending arm of lever 47 turning said lever in the clockwise direction, Fig. 6, thereby elevating the rod 40 and moving the lower 55 contacts 35 into bridging relation with the contacts 37, 38. This operation completes a motor circuit in Fig. 13 from L1 by way of the main switch 100, wire 101, a contact 37, bridge contacts 35, a contact 38, wire 102, 60 the motor armature, wire 103, a contact 37, bridge contacts 35, a contact 38, wire 104 to L2. The motor thereupon rotates in what may be termed the reverse direction (assuming the press closing direction to be the forward direction) and produces rotation of the 65

casing 22 in the clockwise direction, Fig. 1, thereby opening the toggles 7, 9, permitting head 13 to move downwardly and engage the swivel block 6 and then pull down the rear arm of the head lever, thereby opening the 70 press. Rod 85 slides idly through the swivel block 82^a. At the conclusion of the press opening operation the ledge 84 engages the roller 83 and pushes downwardly the link 80 and rod 40, restoring the switch parts to the neutral position shown in the drawing. Since the head lever is the part which performs this switch opening operation the parts are always brought to rest in a definite open 75 position determined by movement of the head 80 lever itself.

Press closing operation is performed by pulling out the button 56 to the position shown in Fig. 6. The operation of the switch parts is the reverse of that before described. Again, as soon as the pivot 50 passes a straight line between the pivot of lever 51 and the swivel block 48 the compression effect of spring 52 completes the movement of the rod 53 on the one hand and pushes over to the right the depending arm of lever 47, thereby pushing downwardly the rod 40 and moving the upper contacts 33 into cooperating relation with the stationary contacts 37 and 38. A forward motor circuit is now established 90 in Fig. 13 from L1 by wire 101, a contact 37, bridge contacts 33, the other contact 37, wire 103, the motor armature, wire 102, across contacts 38 by way of bridged contacts 33 and by wire 104 to L2. The motor now rotates in the forward direction, turning casing 22 in the counter-clockwise direction, Fig. 1, and straightening the toggle members 7, 9. The pressing elements are brought to engaging 95 relation with the work and power pressure is then applied with consequent compression of the spring 15 to such an amount, regardless of the thickness of the work, as to cause the head 13 to rise from the swivel block 6. Collar 85 has engaged swivel block 100 82^a and the upward motion of head 13 therefore turns lever 86 a sufficient amount to raise rod 85 and through the yoke lever 81 to elevate the rod 40 and restore the parts of the reversing switch 32 to their neutral positions, 105 as indicated in Fig. 13. In such position the press and motor parts stop and the press is allowed to remain with full power pressure applied to the work for as long as the operator chooses, when an opening operation is initiated and completed as before.

Each time the rod 40 is moved by actuation of the manually operable rod 53 to initiate a press closing or opening operation the parts of the switch move into current 110 conducting position immediately and without any particular effect upon the spring 42 between the blocks 39, 41. On the other hand when the rod 40 is either raised or moved downwardly automatically by the 115 120 125 130

effect of the ledge 84 on the one hand or the upward motion of the head 13 on the other hand, such switch operations begins with the contacts closed and the first effect is to 5 press the spring 42 and move one insulating block 39 or 41 toward the other until the compression imparted to said spring is sufficient to snap the contacts out of engagement. In other words, this is a quick break, snap 10 reversing switch.

Referring now to the guard, it will be observed that in closed position of the press, shown in Fig. 10, the lower edge of the skirt of the guard lies at practically the meeting plane of the head and bed. Also, the wall of the guard lies very close to the head so that the space 110 between the guard and pressing members is not wide enough to permit the operator to slip her fingers up under 15 the guard and into the space between the pressing members while they are being closed. As the press head rises during the opening movement, the bracket 63^a and clevis 96 (Fig. 10) remain stationary, so that the 20 rod 95 and lever 91 swing about the pivot between rod 95 and clevis 96 as an axis, thereby causing the roller 92 as the head rises to approach and finally engage the plates 94. Until said rollers have engaged said plates, 25 the front arm of the head lever 4 moves upwardly without corresponding upward movement of the guard arms 72. As soon as the rollers 92 engage the plates 94, further upward movement of the head lever causes 30 them to cam the guard arms 72 upwardly, so that the guard begins to move upwardly and with a speed which increases and is faster than that of the head lever. As a consequence in the open press position the 35 guard in its movement has overtaken the earlier moving head and has reached a position in which its lower edge is again opposite the lower edge of the head, so that the guard does not obstruct the entrance to the 40 pressing space. As the head lever moves downwardly toward pressing position the reverse operations occur. During the first downward movement of the head the guard advances ahead of it until finally the guard 45 reaches a position limited by engagement of the screws 99 with the bracket extensions 97, where its lower edge is at the level of the top of the bed. There the guard halts until the head completes its downward motion. 50 The advance of the guard ahead of the head enables the guard to strike an abnormal obstruction, such as the operator's hand or arm, before the press is fully closed and therefore before the operator might be injured. 55 Should the guard encounter such an abnormal obstruction during its downward motion the movement of the guard is halted before it reaches its final downward position shown in Fig. 10, and the relative upward tilting of that part of the guard en-

gaged by the obstruction raises one or the other of the balls 75 and turns the lever 70 in the counter-clockwise direction, Fig. 10, and pulls over the rod 69 to the right in Fig. 7, as described. This operation withdraws the lug 65 from the recess 64, thereby 70 freeing the rod 58 for upward motion produced by compression of spring 61. This is a fairly strong spring and in the position shown in Fig. 7, it is sufficiently compressed 75 so that when released it has power enough to cause the rollers 59 to turn the lever 51 in the counter-clockwise direction and complete the same kind of a press opening operation as is completed by operation of the rod 53, to wit, 80 the full movement of lever 51 in the counter-clockwise direction from the position shown in full lines to that in dotted lines, Fig. 6, not only first moving the reversing switch parts to neutral, but secondarily moving such parts 85 to the motor reversing position, completing the reverse motor circuit before described and causing the motor to rotate in the reverse direction until the pressing parts have been moved to full open position where they are 90 stopped by engagement of the ledge 84 with the roller 83, as before described. After such an emergency stopping and press opening operation the parts are restored to normal position by actuation of the rod 53 for 95 producing the next closing operation, during which operation lever 51 is moved to the position shown in Figs. 6 and 8, the yoke arm 57 of said lever pulling the rod 58 downwardly until the parts 64 and 65 again latch. 100

In this pressing machine the opening position of the parts is always the same, due to the fact that the opening cycle is terminated by the head lever itself, a shoulder on which actuates the switch for opening the motor 105 circuit. As to the closed full pressure position of the pressing members, such position may vary, according to whether the work being operated upon is thick or thin. The spring 15 may be adjusted by adjustment of 110 its abutment 14 to produce any desired predetermined pressure upon the work, say one thousand pounds. When the head is brought into engagement with the work and one thousand pounds pressure has been produced upon 115 the work, spring 15 yields and permits upward motion of the head 13, with consequent action of the switch mechanism in the manner described. If the garment is thick, the toggle members will not be straightened so fully 120 as if a thin piece is iron, but under all conditions the head 13 will travel the predetermined distance when the spring 15 yields and opening the motor circuit and stopping the pressing members with the garment under 125 measured pressure, regardless of its thickness. In this press therefore, regardless of the thickness of the work, the movement of the pressing members during the closing and pressure operations is limited by means sen- 130

sitive to or controlled by a predetermined degree or value of ironing pressure, and such degree or value is readily adjustable by the adjustment of nut 14.

5 Adjustment of the rod 66 in member 67 obviously permits a fine or sensitive adjustment of the operation of the emergency mechanism, so that it can be made to release the rod 58 to movement by the spring 61 upon any degree of movement of the guard.

10 It will also be noted that the guard skirt and frame are of relatively light construction and therefore more or less flexible. In other words, an obstruction at one end of the 15 press may tilt upwardly one end of the guard without producing like motion of the guard at the other end of the press. Nevertheless, the connections in the mechanism from the guard to the switch controlling parts operated thereby are such that wherever any part 20 of the guard is tilted upwardly by an obstruction and consequent rotation of the shaft 71 an operation of the switch parts is produced. Under all circumstances therefore the press 25 is safe to operate and protects not only the operator, but the machine parts as well.

Having described our invention, we claim:

1. A pressing machine, comprising relatively movable pressing members, means for 30 operating said members to produce pressure therebetween, means for limiting the production of pressure by said operating means, and means sensitive to a predetermined value of pressure between said members for causing 35 operation of said limiting means.

2. A pressing machine as claimed in claim 1, in which the operation of the means sensitive to a predetermined value of pressure is unaffected by the thickness of the work.

40 3. A pressing machine as claimed in claim 1, in which the means sensitive to a predetermined value of pressure is adjustable to vary said predetermined value.

45 4. A pressing machine, comprising relatively movable pressing members, means for operating the same and causing ironing pressure therebetween, said means including yieldable connected parts arranged to move relatively to each other as the pressure between said pressing members increases, and means controlled by said parts for limiting the amount of ironing pressure produced between said members to a predetermined value.

55 5. A pressing machine, comprising relatively movable pressing members, means for operating the same and causing ironing pressure therebetween, said means including yieldable connected parts arranged to move relatively to each other as the pressure between said pressing members increases, and means controlled by said parts for limiting the amount of ironing pressure produced between said members to a predetermined value, said parts being adjustable to vary 60 the value of said predetermined pressure.

6. A pressing machine, comprising relatively movable pressing members, a power driven means, means actuated thereby for producing relative approach of said members to cause ironing pressure therebetween, 70 means for stopping the operation of said power driven means and means sensitive to a predetermined value of ironing pressure between said members for causing operation of said stopping means.

7. A pressing machine, comprising relatively movable pressing members, power driven means, means actuated thereby for producing pressure between said members, normal controlling means therefor adapted 80 when operated to cause the power driven means to produce complete pressure operation of said pressing members, and emergency means controlling said power driven means for said pressure producing means adapted 85 when actuated to automatically interrupt the pressure producing operation and cause the pressing members to move to full open position.

8. A pressing machine, comprising relatively movable pressing members, power driven means, means actuated thereby for producing pressure between said members, normal controlling means therefor adapted 90 when operated to cause the power driven means to produce complete pressure operation of said pressing members, normal release means adapted when actuated to cause 95 release of the pressing members to full open position, and emergency controlling means 100 for said pressure producing means adapted when actuated to automatically interrupt the pressure producing operation and cause the pressing members to move to full open position.

9. A pressing machine, comprising relatively movable pressing members, power operated means for producing pressure between said members and arranged to be capable of reverse operation for opening the 110 press, normal controlling means adapted when operated to cause the power operating means to produce complete pressure operation of said pressing members, and emergency controlling means adapted when actuated to automatically interrupt the pressure producing operation and cause reverse operation of said power operating means to open the press.

10. A pressing machine, comprising relatively movable pressing members, power 120 operated means actuated to produce closing operation of said members and capable of reverse operation to open the press, normal controlling means therefor adapted to produce closing and opening movement of the 125 press, a guard for the entrance to the pressing space, and means actuated by said guard under emergency conditions for causing reverse operation of said motor means to open the press.

11. A garment press, comprising relatively movable pressing members, operating mechanism for producing relative motion of said members and including a reversible electric motor, means for normally operating said motor to apply and relieve pressure, and additional emergency means operatively connected to said motor for producing reverse operation thereof to open the press. 5
12. A garment press, comprising relatively movable pressing members, operating means for producing relative movement of said members and including a reversible electric motor, means for producing forward rotation of said motor to apply pressure to the work, means for causing operation of said motor to open the press under normal conditions, and emergency means for producing reverse rotation of said motor to open the press when closing movement of the pressing members is obstructed. 10
13. A garment press, comprising relatively movable pressing members, operating means therefor including a reversible electric motor, a reversing switch for producing forward and reverse motor circuits, manually operable means for closing said switch to produce either of said circuits, and additional means operatively connected to the moving press parts for opening said switch from its two closed positions. 15
14. A garment press, comprising relatively movable pressing members, operating means therefor including a reversible electric motor, a reversing switch for producing forward and reverse motor circuits, manually operable means for closing said switch to produce either of said circuits, means operated by the moving press parts for opening said switch from its two closed positions, and emergency means connected to said switch and adapted to operate the same to reverse the motor circuit when closing movement of the pressing members is obstructed. 20
15. A garment press, comprising relatively movable pressing members, power means for closing the same and applying pressure thereto, a controller therefor, a guard having a portion extending along the edge of the head and adapted to engage and be moved by any obstruction to closing movement of the pressing members and connections from said guard to said controller, and means sensitive to tilting movement of said guard and operatively connected to said controller for actuating the same to interrupt the operation of the power means. 25
16. A garment press, comprising relatively movable pressing members, power means for closing and opening the same and including a reversible motor, a guard having a skirt portion extending along the edge of the head, and means connecting said guard to the upper pressing member and so arranged that the guard lies opposite the upper pressing 30
- member in open and closed positions thereof and advances ahead thereof during closing movement of the press. 70
17. A garment pressing machine, comprising relatively movable pressing members, a reversible electric motor for producing opening and closing movement thereof, and epicyclic oscillatory speed reducing gearing between said motor and said pressing members. 75
18. In a pressing machine the combination of cooperating pressing elements one of which is movable toward and from the other, power means for actuating the movable element, means for controlling the actuation of the movable element by the power means including mechanism operated by a predetermined maximum pressure of the movable element on the other element, said mechanism including a shiftable part normally in one position whereby the power from the power means is effectively applied and shiftable out of such position by the predetermined maximum pressure. 80
19. In a pressing machine, the combination of cooperating pressing elements, one of which is movable toward and from the other, power means for actuating the movable element and means for controlling the actuation of the movable element by the power means comprising an electric feed circuit, an electric motor in said circuit, an electric switch and means controlled by a predetermined maximum pressure between said elements for throwing said switch to break the circuit through the motor. 85
20. In a pressing machine, the combination of cooperating pressing elements, one of which is movable toward and from the other, means for actuating the movable element, including an electric motor and an electric feed circuit connected to said motor, manual means for closing the circuit through the motor to close the press, an electric switch in said circuit and means controlled by the pressure applied by the movable element to actuate the switch to open said circuit, and means for opening the press, comprising a manually operable switch for closing the circuit through the motor when the press is closed. 90
